PISTON CONSTRUCTION

Virgil R. Johnson, Detroit, Mich., assignor to
 Virgil R. Johnson Company, Detroit, Mich., a
 corporation of Michigan

Application March 5, 1934, Serial No. 713,984

5 Claims. (Cl. 309—11)

This invention relates to pistons for internal combustion engines.

The principal object of the invention is to provide an improved piston construction for internal combustion engines.

Another object is to provide means for preventing "piston slap" in the operation of an internal combustion engine.

A further object is to make provision for taking up clearance due to wear between the wrist pin and the bearings therefor which are secured to the piston.

Another object is to provide a composite piston construction in which integral piston head and skirt portions are detachably secured to the wrist pin bearings so that the piston may be detached and removed from the head end of the cylinder of an internal combustion engine.

A further object is to minimize oil pumping, leakage by the piston, and wear of cylinder walls.

Still another object is to provide a piston adapted to function efficiently in worn or out-of-round cylinders, thus obviating the necessity of reborning cylinders.

Other objects, features and advantages will become apparent from the following description and appended claims.

For the purpose of illustrating the genus of the invention, a typical concrete embodiment thereof is shown in the accompanying drawing, in which:

Figure 1 is a side elevation, with parts broken away, of a piston constructed in accordance with the principles of the present invention;

Fig. 2 is a central, vertical section taken on the line 2—2 of Fig. 1, certain elements being shown partly in elevation;

Fig. 3 is a horizontal section taken on the line 3—3 of Fig. 1, and

Fig. 4 is a perspective detail of a part shown in Figs. 2 and 3.

Referring to the drawing, the numeral 10 designates a piston comprising head and skirt portions 11 and 12. Ring grooves 13 are provided in the outer peripheral walls of the skirt portion adjacent the head 11 for the reception and compression of oil rings 14.

The skirt portion 12 is further provided with a pair of integral annularly directed strips 15 and 16 severed therefrom except at one end, as indicated at 18. The strips 15 and 16 are severed more than half way around the piston leaving unsevered portions on diametrically opposite sides of the piston so that both the ends 18 fixed to the piston skirt and the free ends 19 of the strip por-

tions cross or overlap with respect to the longitudinal dimension of the piston.

The strip portions 15 and 16 are expanded outwardly from the skirt portion 12 of the piston by leaf or straw spring members 20 engaging the inner surfaces of the strip member throughout practically their entire length. The annularly directed strip portions 15 and 16 of the piston skirt are arranged one above and the other below the axis of the wrist pin 23 employed for pivotally connecting the piston to the connecting rod 24. The details of the mechanism for connecting the wrist pin to the piston will be described at a later point. By arranging the strip portions 15 and 16 at approximately equal distances above and below the axis of the wrist pin these strip members, expanded outwardly by the spring elements 20, will resiliently engage the walls of a cylinder in which the piston is adapted to reciprocate and prevent "piston slap" during operation of an internal combustion engine. The strip members will also aid in preventing the passage of gases or fuel between the piston and the cylinder walls and will prevent pumping of oil by the piston.

The wrist pin 23 is journaled for rotation in a pair of bearing members 26 and 27 each comprising an upper bearing half 30 and a lower bearing half 31 with the upper and lower bearing halves of each bearing member detachably connected by securing bolts and nuts 33. Shims 34 are removably interposed between the upper and lower bearing halves to take up clearance between the wrist pin and the bearing members therefor as these elements wear during operation. An integral T-shaped head 35 is provided on the upper portion of each of the bearing halves 30 and longitudinally directed threaded openings 36 are provided in the head portions for the reception of bolts 37 projected through openings 40, complementary with the opening 36, for securing the bearing members to the piston head 11. Gasket members 41 are preferably disposed about the securing bolts 37 between the heads thereof and the upper surface of the piston 10 to prevent leakage to the piston head. The heads of the securing bolts 37 are preferably provided with transverse openings 42 through which a loop of wire 43 may be passed and the ends thereof twisted together to prevent rotation of the securing bolts and loosening of the connection between the piston head and wrist pin bearing member. The securing bolt and nut assemblies 33 for adjustably connecting the upper and lower bearing halves 30 and 31 may also be provided with locking means such as cotter pins 46 and lock washers 47 to prevent

loosening of the connection between the wrist pin bearing members and the wrist pin. The upper end of the connecting rod 24 is in the form of a small end bearing 50 adapted to receive the 5 central portion of the wrist pin 23, and the adjacent portion of the connecting rod is split as indicated at 51 so that a transversely disposed tightening bolt 52 can be locked by means of a split washer 53 to clamp the small end bearing 10 of the connecting rod to the wrist pin. An upwardly projecting boss 54 is provided on the upper surface of the piston head 11 and may be manually engaged to withdraw the piston 10 out of engagement with the wrist pin bearings 27 and 15 26 after the securing bolts 37 have been removed.

By virtue of the detachable connection between the piston 10 and the wrist pin bearings 26 and 27, the pistons can be removed from the cylinder simply by removing the cylinder head and then 20 removing the securing bolts 37. This facilitates the replacement of the compression and oil rings 14 by simply removing the cylinder head rather than removing the oil pan of the engine and disconnecting the crankshaft bearings. It is also 25 noted that in the present construction the annularly directed strip members 15 and 16 are composed of the same material as the piston, preferably of aluminum composition, so that they will cause very little wear of the cylinder walls and in 30 conjunction with springs 20 will take care of any wear of the cylinder walls which has previously occurred whether the cylinder walls are out of round or not.

As many changes could be made to the above 35 described construction and many apparently widely different embodiments of this invention could be made without departing from the spirit thereof, it is intended that all matter contained in the above description or shown in the accompanying 40 drawings shall be interpreted as illustrative and not in a limiting sense.

What is claimed is:

1. A piston comprising head and skirt portions, 45 said skirt portion having spaced, integral and annularly directed strip portions severed therefrom except at one end of each strip portion, said strip portions being located at intermediate zones of said skirt portion and extending in opposite directions more than half way around the 50 periphery of said skirt portion, and spring means engaging the inner surfaces of said skirt and strip portions for expanding the latter radially outwardly with respect to the skirt portion.

2. A piston including head and skirt portions, 55 said skirt portion including integral annularly

directed strip portions each extending more than half way around the piston and severed except at one end thereof from the piston, said strip portions being located at intermediate zones of the skirt portion, and resilient means engaging the inner surfaces of the strip portions throughout practically their entire lengths for expanding the strip portions outwardly with respect to the remainder of the skirt portion. 5

3. A piston including head and skirt portions, 10 said skirt portion including annularly directed strip portions each extending more than half way around the piston and severed except at one end thereof from the piston, said strip portions being located at intermediate zones of the skirt 15 portion, and leaf springs each engaging the inner surface of a strip portion throughout practically its entire length for expanding the strip portion outwardly with respect to the remainder of the skirt portion. 20

4. In combination with a piston including head and skirt portions, a wrist pin, a pair of separate wrist pin bearing members each comprising bearing halves and means for adjustably securing said bearing halves around said wrist pin, and means 25 for detachably securing said bearing members to the head portion of said piston, said second-named securing means being accessible from the head end of said piston and said separate bearing members being accessible from the same direction after 30 the first-named securing means and the piston are removed, said wrist pin and bearing members being so constructed and arranged that each bearing member may be removed from the wrist pin without dis-assembling the bearing halves and 35 without moving the wrist pin or bearing members beyond the lateral limits of the space normally occupied by the piston.

5. In combination with a piston including head and skirt portions, a wrist pin, a connecting rod 40 including a wrist pin engaging end and means for adjustably clamping said wrist pin against relative movement within such engaging end, a pair of wrist pin bearing members each comprising bearing halves and means for adjustably securing said bearing halves around said wrist pin, and means for detachably securing said bearing members to the head portion of said piston, said second-named securing means being accessible from the head end of said piston and said adjustable clamping means and said first-named securing means being accessible from the same direction after the first-named securing means and piston are removed. 50
